UNITED STATES PATENT OFFICE.

ARTHUR W. KOON, OF ONARGA, ILLINOIS.

COMBINED GRAIN DUMP AND ELEVATOR.

SPECIFICATION forming part of Letters Patent No. 715,818, dated December 16, 1902.

Application filed October 31, 1901. Serial No. 80,676. (No model.)

To all whom it may concern:

Be it known that I, ARTHUR W. KOON, a citizen of the United States, residing at Onarga, in the county of Iroquois and State of Illinois, 5 have invented a certain new and useful Combined Grain Dump and Elevator, of which the following is such a full, clear, and exact description as will enable others skilled in the art to which my invention appertains to 10 make and use the same.

My invention relates to apparatus for dumping grain from a wagon and conveying same to a car, crib, bin, or other suitable receptacle.

15 The purposes of my invention are to provide means for tipping the front end of a wagon so that the grain contained therein will be discharged on a suitable conveyer, to provide simple and effective means for conveying the grain to the elevator, to provide means for elevating the grain, to provide means to prevent excessive tipping of the wagon, to provide means for gradually lowering the wagon after it has been raised, to provide 20 means adapting the conveyer to be swung away from the wagon, so as to not interfere with bringing the wagon into position to be tipped, and to provide an extensible elevator of novel and improved construction.

25 With these ends in view my invention consists in the novel features of construction and combinations of parts shown in the annexed drawings, to which reference is hereby made, and which are hereinafter particularly described, and finally recited in the claims.

30 Referring to the drawings, Figure 1 is a top plan of the complete apparatus. Fig. 2 is a vertical transverse section on the line 2-2 of Fig. 1. Fig. 3 is a vertical longitudinal section on the line 3-3 of Fig. 1. Fig. 4 is an enlarged end elevation of the left-hand end of the lifting device. Fig. 5 is a vertical transverse section through the elevator and its supporting-standard on the line 5-5 of Fig. 45 2. Fig. 6 is an enlarged partial front elevation of that part of the mechanism contiguous to the left-hand end of the platform A². Fig. 7 is a vertical section on the line 7-7 of Fig. 6, and Fig. 8 is a partial vertical section 50 taken on the line of the axis of the shaft A⁶.

Similar letters of reference designate like parts in all of the views.

The means for tipping the wagon consists of a platform slidable between vertical guides and provided with means for stopping the 55 platform when it has been raised to a predetermined height.

Vertical posts A have their lower ends secured to suitable base-pieces A' and their upper ends connected by cross-pieces A³. A platform A² is slidable between the pair of posts A. Brackets A⁴ are secured to the platform A², and wheels A⁵, mounted on the brackets, travel between the posts and prevent binding of the platform against the 65 posts. A shaft A⁶ is secured on the cross-pieces A³. Sheaves A⁷ are mounted to turn on the shaft A⁶. A shaft A⁸, mounted to turn in suitable bearings, extends lengthwise under the platform A² and carries a miter 70 gear-wheel A⁹, which meshes with a corresponding miter-wheel B', secured on the main shaft B, which is driven by a horse-power or other suitable motor. A tubular shaft A¹⁰ incloses the shaft A⁸ and has at its ends spools 75 A¹², which are secured to and turn with the shaft A¹⁰. A clutch member A¹³ is secured to the shaft A⁸ and engages with a corresponding member on the tubular shaft A¹⁰. Cords A¹⁴ are secured to the spools A¹², pass 80 around the sheaves A⁷, and are secured to extensions a on platform A² in such manner that the winding of the cords on said spools will serve to raise the platform, and the cords will be unwound from the spools as the platform descends.

A lever A¹⁵ is fulcrumed on a pin a' on one of the posts A and has at its lower extremity a fork a³, which spans the shaft A¹⁰ and engages with the spool A¹², so that when the lower 90 end of the lever is thrown to the left the fork will act against the spool to move the tube A¹⁰ to the left, so as to disengage the clutch A¹³. A spring A²⁰ surrounds the shaft A¹⁰ and acts against a collar a⁴ on the shaft to slide the 95 shaft to the right, so as to bring the clutch A¹³ into engagement when the upper end of the lever A¹⁵ is released. The upper end of the lever A¹⁵ is shifted to the right by the extension a, engaging with the lower part a² of the 100

lever A¹⁵, and is caught and retained by a spring-latch A¹⁶, engaging with the upper end of the lever and serving to hold the clutch out of engagement.

5 A wheel A¹⁷ is secured on the shaft A¹⁰. A strap A¹⁸ fits around the perimeter of the wheel A¹⁷ and is operated by a lever A¹⁹, mounted on one of the posts A, so that the strap pressing against the perimeter of the wheel serves 10 as a brake to control the descent of the platform.

In practical use the wagon containing the grain to be dumped is placed with its front wheels resting on a platform A². The latch 15 A¹⁶ is then released, so as to permit the clutch to come into engagement. The clutch being in engagement, the shaft A¹⁰, driven by the shaft B, winds the cords A¹⁴ on the spools A¹², and thereby raises the platform until the lever A¹⁵ is operated to disengage the clutch. A ratchet-wheel A²¹ on the shaft A¹⁰ is engaged by a pawl A²² to prevent premature descent of the platform. When it is desired to lower the platform, the pawl A²² is released 20 and the brake applied so as to cause the platform to descend gradually until it returns to its initial position, when the wagon may be withdrawn and another substituted, and so on as long as the apparatus may continue in 25 operation.

The conveyer mechanism consists of an endless conveyer of the usual well-known form, mounted on a standard in such manner that the conveyer may be swung forwardly or rearwardly, so as not to interfere with placing the wagon in proper position on the platform A² and so that when the wagon is in position the conveyer may be swung around to occupy a 35 position under and transverse to the rear end of the wagon.

The standard D is secured on any suitable base D', and its lower part d is arched to accommodate a pair of miter-gears, as shown. A tubular shaft D³ is mounted to turn in the 45 standard D and has a polygonal bore in which a polygonal shaft D² is slidable. A collar d² is secured on the shaft D², and that part of the shaft above the collar is round. A yoke D⁴ is supported on the collar d² on the shaft 50 D², and the yoke turns on the shaft. A miter-gear D⁶ is secured on the upper end of the shaft D² and meshes with a similar gear D⁸ on the shaft D⁷, mounted to turn in the yoke D⁴. A roller D¹⁰ is secured on a shaft which 55 turns in bearings on the yoke D⁴. A cog-wheel D¹¹ on the shaft of the roller D¹⁰ meshes with a similar cog-wheel D⁹ on the shaft D⁷. A miter-wheel D¹³ is secured near the lower 60 extremity of the tubular shaft D³ and meshes with a similar wheel D¹⁴, secured on shaft B. Side-boards D¹⁵ are supported on the shaft of the rollers D¹⁰. An endless belt D¹² is carried on the rollers D¹⁰. A bail D¹⁶ at the free end of the elevator serves as a means for supporting the outer end of the elevator by connecting the bail to any suitable support.

By reason of the construction shown and described the elevator may be raised or lowered or may be swung rearward or forward at pleasure without interfering with the operation of the elevator.

A chute E, supported in any suitable manner, receives the grain as it is discharged from the conveyer and carries it into position to be taken up by the elevator.

75 The elevating mechanism is carried on a rectangular extensible structure supported on the base D'. Tubular corner-posts F are suitably secured to the base and are connected by cross-pieces F². Rods F' are slidable in the corner-posts F and are connected by cross-pieces F³ and when placed in any desired position may be secured by set-screws f.

A bracket F¹⁴ supports a central upright F⁴, which is secured immovably and centrally 80 within the lower section of the frame. A similar upright piece F⁵ is secured at its upper end to a bracket F¹³ at the upper end of the upper section of the frame and is slidable on the central upright in the lower section of 85 the frame. A rack F⁶ on the upright F⁵ meshes with a cog-pinion F⁷, mounted on a shaft F⁸ on the upright F⁴ and provided with a crank F⁹, by which the shaft may be turned, so as to cause the pinion to operate in the 90 rack in such manner as to raise or lower the upper section of the frame. A ratchet-wheel on shaft F⁸ is engaged by a pawl f' to prevent backward turning of the shaft. The upper sprocket-shaft F¹⁵ turns in suitable bearings in the bracket F¹³, and the lower shaft F¹⁰ turns in suitable bearings in the lower bracket F¹⁴. Sprocket-wheels F¹¹ carry endless chains F¹², to which the elevator-buckets F¹⁶ are secured. The shaft F¹⁰ carries near 105 its outer extremity a sprocket-wheel F¹⁷, which is connected by a sprocket-chain F¹⁸ with a similar sprocket-wheel B² on the main drive-shaft B.

The elevating-frame is made extensible in 110 order that it may be used with cribs or bins of different heights. When it is desired to extend the frame, the elevator-chains are unhooked and the crank F⁹ is then turned to raise the upper section to the desired height. 115 Additional links are then placed in the chain F¹² to make them conform to the increased height of the frame. To shorten the frame, this operation would be reversed.

The operation of the apparatus is as follows: The conveyer is first swung rearward, so that the wagon loaded with grain may pass the conveyer and the wagon may stop with its front wheels resting on the platform A². The elevator is then swung forward, so as to 125 lie under and transverse to the rear end of the wagon-bed, and the outer end of the elevator is secured in any suitable manner to keep it in the desired position. The mechanism for lifting the platform A² is then 130 started, and the platform as it rises lifts the front part of the wagon, so that the grain

contained in the wagon-bed slides out of the bed onto the conveyer and is carried by the conveyer and deposited on the chute, from which it slides into position to be caught and carried upward by the elevator-bucket, from which it is dropped into the bin or other receptacle.

Having fully described my invention, what I claim as new, and desire to secure by Letters

10 Patent, is—

15 1. A lifting device for an apparatus of the class described, consisting of upright posts, a platform slideable between said posts, a shaft rotatable under said platform, a clutch member on said shaft, a tubular shaft inclosing said first-named shaft and having spools and a clutch member, rotatable sheaves at the upper end of said posts, cords secured to spools, passing around said sheaves, and connected with said platform, a lever mounted on one of said posts and adapted to disengage said clutch, means for operating said lever

by the upward movement of the platform and a latch engaging with said lever, substantially as set forth.

2. In an apparatus in the class described the combination of a rotatable shaft, a tubular sleeve inclosing said shaft, a clutch member on said shaft, a clutch member on said sleeve, a spring acting to hold said clutch member in engagement, a vertically-movable platform, means for lifting said platform by the rotation of said sleeve, means for retaining said platform in its raised position and means for gradually lowering said platform, as set forth.

In witness whereof I have hereunto subscribed my name, at Onarga, Illinois, this 29th day of July, 1901.

ARTHUR W. KOON.
